INVENTOR

A. Eggendorfer

UNITED STATES PATENT OFFICE.

AUGUST EGGENHOFER, OF ZANESVILLE, OHIO.

CUSPIDOR.

No. 925,998.

Specification of Letters Patent.

Patented June 22, 1909.

Application filed October 26, 1907. Serial No. 399,318.

To all whom it may concern:

Be it known that I, AUGUST EGGENHOFER, a citizen of the United States, residing at Zanesville, in the county of Muskingum and 5 State of Ohio, have invented certain new and useful Improvements in Cuspidors; and I do hereby declare the following to be a full, clear, and exact description of the invention, such as will enable others skilled in the art to 10 which it appertains to make and use the same.

My invention relates to new and useful improvements in self-cleaning, sanitary cuspidors, and my object is to provide means for 15 automatically directing a stream of water through the cuspidor with each removal of the cover therefrom.

A further object is to so locate the cuspidor in the floor as to cause the least obstruction.

Other objects and advantages will be hereinafter referred to and more particularly pointed out in the claim.

In the accompanying drawings which are 25 made a part of this application, Figure 1 is a perspective view of the cuspidor applied to use and showing the cover therefor in its open position, and, Fig. 2 is a sectional view showing the manner of securing the cover to 30 the valve stem.

Referring to the drawings in which similar reference numerals designate corresponding parts throughout the several views, 1 indicates the bowl of my improved cuspidor, 35 which is preferably semi-globular and provided around its upper edge with a flange 2, the bowl being preferably entered through an opening in the floor 3 of a room, the upper surface of the floor having a recess 4 therein 40 to receive the flange 2, thereby disposing the upper face of the flange flush with the upper face of the floor.

One section of the bowl 1 is provided with a rib 5, which is adapted to hold the bowl 45 against rotating movement.

A drain pipe 6 is secured to the lower end of the bowl 1 in the usual or any preferred manner, said pipe being bent in the usual manner to form a seal for the drain pipe. A 50 service pipe 7 is also connected to the bowl 1 and at a point adjacent its upper edge, the pipe 7 preferably entering the bowl at a tangent to the axial center of the bowl, so that the water will be thrown around the edges of 55 the bowl and, to insure that the water will engage the entire inner surface of the bowl, a

channel 8 is formed in the inner edge of the bowl through which the water passes from the pipe 7, said channel serving to direct the water around the wall of the bowl. The pipe 60 7 is provided at a point adjacent its connection with the bowl, with a valve 9, the stem 10 of said valve extending upwardly through the floor 3 and has fixed thereto a cover 11, said cover being adapted to snugly fit over the upper surface of the bowl and exclude the same from view when not in use and by squaring the upper end of the stem 10 and forming a square opening in the cover 11, the stem 10 will be rotated to open or close the 70 valve when the cover is moved to one side of or over the bowl, respectively, the cover being held in position on the stem by introducing a screw 12 into the upper end of the stem, the head of the screw over-hanging the parts 75 of the cover engaging the stem and in order to operate the cover, a knob 13 is secured to the upper surface thereof, so that by engaging the knob with the hand or the foot, the cover may be readily operated. The service 80 pipe 7 is further provided with a cock 14, so that the supply of water may be entirely cut off from the bowl and access to the cock is readily attained by providing a trap 15 in the floor 3, immediately above the cock. 85

In operation, when a person wishes to expectorate, the cover 11 is swung laterally from over the bowl, by engaging the knob 13 and preferably with the foot, the operation of swinging the cover, opening the valve 9, so 90 that the water from the service pipe will flow into the bowl, the water continuing to flow as long as the cover is open. As soon, however, as the cover is again closed, or placed over the bowl, the valve 9 will be closed and the 95 flow of the water into the bowl stopped and it will be readily seen that by so flushing the cuspidor, the same will be thoroughly sanitary and it will further be seen that by placing the same through the floor, as shown in 100 the drawing, said cuspidor will present practically no obstruction in the room.

What I claim is:

The herein described cuspidor incorporated into a floor, comprising a bowl member, 105 said bowl member having a vertical rib integral with the outer face thereof and adapted to engage parts of said floor and hold said bowl against rotation, a pipe for conveying water into the upper edge of said bowl and 110 directing the same at a tangent to the vertical axis of the bowl, a valve located in the

length of said pipe having an upwardly extended stem protruding through said floor, a closure fixed in said stem whereby when said closure is swung laterally the valve will be opened or closed, and a drain pipe connected to said bowl.

In testimony whereof I have signed my

name to this specification in the presence of two subscribing witnesses.

AUGUST EGGENHOFER.
